The ornamental design for a cosmetic container, as shown and described.

DESCRIPTION

FIG. 1 is a perspective view of a cosmetic container showing my new design view;

FIG. 2 is a front elevational view thereof, which is the same as a rear elevational view, a left side elevational view, and a right side elevational view thereof;

FIG. 3 is an enlarged top plan view thereof; and,

FIG. 4 is an enlarged bottom plan view thereof.

The broken lines in the drawings showing the cosmetic container illustrate the portions of the cosmetic container that form no part of the claimed design.
